US00D585888S

(12) **United States Design Patent**
Watson et al.

(10) **Patent No.:** **US D585,888 S**
(45) **Date of Patent:** **** Feb. 3, 2009**

(54) **ELECTRONIC DOCUMENT READER**

(75) Inventors: **Ben Watson**, Hertfordshire (GB); **Nick Sandham**, London (GB); **Duncan Barclay**, Cambridgeshire (GB); **Simon Jones**, Cambridgeshire (GB); **Carl Hayton**, Cambridgeshire (GB); **David Fisher**, Middlesex (GB); **Anusha Nirmalanathan**, Cambridge (GB)

(73) Assignee: **Plastic Logic Limited**, Cambridge, Cambridgeshire (GB)

(**) Term: **14 Years**

(21) Appl. No.: **29/278,503**

(22) Filed: **Mar. 30, 2007**

(51) **LOC (9) Cl.** **14-02**

(52) **U.S. Cl.** **D14/341**

(58) **Field of Classification Search** ..... **D14/345, D14/482, 496, 371, 129, 373, 341-344, 346, D14/420-425, 315, 316, 318, 439-441, 432, D14/322-327, 457, 458, 447, 406.4, 114, D14/401, 454; 345/619, 173, 901, 206, 100, 345/107, 1.1, 204, 533, 1.3, 156, 169; 434/317, 434/169, 308, 178, 156, 167, 307 R, 309; 361/681, 685, 686; 369/292; 235/375, 145 R, 235/145 A; 348/836, E5.128; 358/527, 474, 358/444; D6/300, 308, 406.1-406.6, 574, D6/567, 511; 715/273; 132/216; D28/36, D28/77, 64.3, 83, 78; 206/581; 402/4; 281/22, 281/29, 51; D21/330, 333; 367/68; D19/35, D19/52, 26, 59, 60; 349/12; 178/18.03; D8/323, 353, 331, 344; 341/22-23; D13/119, D13/103, 156, 110; D3/212, 901; D9/424, D9/414, 435, 439, 445, 455-457, 449; 429/175, 429/176, 163-166, 136; 455/128; 174/138 F; 248/678, 441.1**

(57) **CLAIM**

The ornamental design for an electronic document reader, as shown and described.

DESCRIPTION

FIG. 1 is a front elevational view of a first embodiment of the electronic document reader of the present design;

FIG. 2 is a rear elevational view of the electronic document reader of FIG. 1;

FIG. 3 is a left side elevational view of the electronic document reader of FIG. 1;

FIG. 4 is a bottom side elevational view of the electronic document reader of FIG. 1; and,

FIG. 5 is a front, left side, and bottom side perspective view of the electronic document reader of FIG. 1.
